UNITED STATES PATENT OFFICE.

RAGNAR WIKANDER, OF PITTSBURGH, PENNSYLVANIA, ASSIGNEE TO WESTINGHOUSE ELECTRIC AND MANUFACTURING COMPANY, A CORPORATION OF PENNSYLVANIA.

SWITCH FOR ELECTRIC CIRCUITS.

1,241,592.

Specification of Letters Patent.

Patented Oct. 2, 1917.

Application filed March 23, 1911. Serial No. 616,780.

To all whom it may concern:

Be it known that I, RAGNAR WIKANDER, a subject of the King of Sweden, and a resident of Pittsburgh, in the county of Allegheny and State of Pennsylvania, have invented a new and useful Improvement in Switches for Electric Circuits, of which the following is a specification.

My invention relates to switches for electric circuits and particularly to such switches as are operated or controlled by electro-magnets.

The object of my invention is to provide a switch of the character above indicated that shall be very positive in its operation and easily adjustable to vary the conditions under which it will operate.

In my co-pending application, Serial No. 616,474, filed of even date herewith, I have shown and described an electro-magnetically operated switch that possesses the characteristic of operating only when the current supplied to the magnet coil falls within predetermined limits.

According to my present invention, I provide a switch and an operating or controlling electro-magnet therefor which possesses similar characteristics, but which is different in structure and is provided with two opposed magnet coils.

Figure 1 of the accompanying drawings is a side elevation, and Fig. 2 a front view of a switch constructed in accordance with my invention. Figs. 3 and 4 are sectional views of modified structures embodying my invention, and Fig. 5 is a sectional view of a switch adapted to be operated by fluid pressure and having a control valve which is governed by an electro-magnet constructed in accordance with my invention.

Referring to Figs. 1 and 2 of the drawings, the structure here shown comprises a substantially E-shaped core member 1 having outwardly projecting arms 2, 3 and 4, movable armatures 5 and 6, a stationary switch contact member 7, and a co-operating movable contact member 8. The movable armatures 5 and 6 are pivotally mounted on a shaft 9, supported by projections 10 and 11 which extend outwardly from the core member 1, at the respective sides of the core member 3. The movable contact member 8 is secured to a contact-bearing member 12

having a projection 13. The armature 6 is provided with a projection 14 having a hole 15 through which a rod 16 extends. The rod 16 is pivotally secured to the projection 13 of the member 12 and has a washer or enlargement 17 which limits the permissible separation between the projections 13 and 14, an interposed spring 18 tending to force the projections apart. The armature 5 is connected to the projection 14 of the armature 6 by springs 19 which tend to pull the armatures out of alignment and to bring a stop projection 20 into engagement with a lug 21 on the projection 14. The arms 2 and 4 are respectively provided with magnetizing windings 22 and 23 which act in opposition to each other.

The operation of the switch is as follows:

Assuming that the windings 22 and 23 are deenergized, armature 6 is moved by gravity into engagement with arm 4, and projection 20 engages lug 21, the switch contacts 7 and 8 being separated. The spring 18 forces a projection 24 of the member 12 into engagement with lug 25 of the armature 5 before it is separated from the arm 2, so that the switch contacts are not brought into engagement. If, under the conditions just outlined, energy is supplied to the winding 22 from a constant source, and if the winding 23 is supplied with a variable current, as would be the case if connected in series with a motor at starting, the parts will assume the positions indicated in Fig. 1 of the drawings, the armatures 5 and 6 being respectively brought into engagement with the arms 2 and 4. The switch contact members 7 and 8 are still separated by reason of the rod 16 which constitutes a connection between the armature 6 and the contact-bearing armature 12. As soon as the current traversing the coil 23 decreases sufficiently, the springs 19 will overcome the attraction between the members 6 and 4 and will bring the lug 21 into engagement with the projection 20, the spring 18 forcing the contact 8 into engagement with the contact 7, at the same time. After the switch is closed, if the current traversing the coil 23 becomes sufficiently excessive, the armature 6 will again be brought into engagement with the arm 4 and the switch will be opened.

As shown in Figs. 3 and 4 of the drawings, substantially the same results may be secured by utilizing two electro-magnets which are connected mechanically only and which act in opposition to each other.

In Fig. 3, movable contact member 8 is actuated by a rod 26 having a movable armature 29 at its lower end and intermediate enlargements 27 and 28. A relatively movable armature 30 is loosely mounted upon the rod 26 between the enlargements 27 and 28 in conjunction with a compression spring 31. A stationary core member 32 and winding 33 are associated with the movable armature 30 and the stationary core member 34 and a winding 35 are associated with the armature 29. Energization of the winding 33 tends to close the switch 8 except when the spring 31 is compressed by the excessive energization of the coil 35.

In Fig. 4 the spring 31 is replaced by weights 36 which act in opposition to the armature 29 and tend to close the switch when the coil 33 is energized and the movable armature 37, which corresponds to the armature 30 of Fig. 3, is raised.

The armatures 29 and 37 are connected to opposite ends of a lever 38 which is pivoted at 39 and is divided into two parts which act together in one direction but which tend to separate in the opposite direction by reason of a projection 40 of one part which engages the body of the other part.

Referring to Fig. 5 of the drawings, a movable contact member 41 is actuated by a rod 42 to which a piston 43 is secured. A spring 44, located within a cylinder 45, tends to hold the switch open, and air pressure, or other fluid pressure, when admitted to the opposite side of the piston through control valve 46, moves the contact member 41 into engagement with stationary contact member 47.

The control valve 46 is normally closed by a spring 48, but, when sufficient pressure is brought to bear on the end of valve stem 49, the valve is opened to admit fluid pressure to the cylinder 45 below the piston 43, whereby the latter is forced upward in opposition to the spring 44. The valve stem 49 is controlled by an arm 50 pivoted on a shaft 51 and connected by a spring 52, to a movable armature 53 of a governing electro-magnet. The electro-magnet comprises, in addition to the armature 53, a stationary E-shaped member 54, a movable armature 55 and coils 56 and 57. The armatures 53 and 55 are both mounted upon the shaft 51, and the spring 52 tends to separate the armature 53 from an arm 58 of the member 54. The coils 56 and 57 act in opposition to each other and the parts 50 and 55 are either integral, as shown in the drawings, or are operatively connected so that energization of the winding 57 tends merely to put the

spring 52 under tension until the current traversing the coil 56 falls below a predetermined value, when the spring is permitted to actuate the valve stem 49 and close the main switch.

Structural modifications may be effected in the switch and magnet which constitute my invention without departing from its spirit and scope, as set forth in the appended claims.

I claim as my invention:

1. A switch for electric circuits comprising stationary and movable contact members, a substantially E-shaped stationary core member, a pair of movable armatures pivoted at the outer end of the intermediate arm of the E-shaped core member, a yielding connection between the two movable armatures tending to prevent their simultaneous engagement with the corresponding arms of the stationary core member, said movable contact member being supported on one of said movable armatures, and means for energizing said core members.

2. A switch for electric circuits comprising stationary and movable contact members, a substantially E-shaped stationary core member, a pair of movable armatures pivoted at the outer end of the intermediate arm of the E-shaped core member, a yielding connection between the two movable armatures tending to prevent their simultaneous engagement with the corresponding arms of the stationary core member, said movable contact member being pivotally supported on one of said movable armatures and yieldingly connected to the other armature, and means for energizing said core member.

3. A switch for electric circuits comprising stationary and movable contact members, a substantially E-shaped stationary core member, a pair of movable armatures pivoted at the outer end of the intermediate arm of the E-shaped core member, a yielding connection between the two movable armatures tending to prevent their simultaneous engagement with the corresponding arms of the stationary core member, opposed magnet coils respectively mounted on the outer arms of the stationary core member, said movable contact member being responsive to the action of one of said movable armatures.

4. A switch comprising stationary and movable contact members, and operating mechanism therefor comprising a pair of relatively movable armature members having a common pivotal support, a spring for yieldingly connecting said armature members, a shunt coil for actuating one of said armature members to place said spring under stress and a series coil for actuating the other of said armatures to oppose the force of said spring and for permitting the en-

gagement of said contact members when the current traversing the series coil falls to a predetermined value.

5. A switch comprising a pair of relatively movable contact members, a pair of opposed magnet windings respectively connected in series and in shunt relation to said switch, means comprising a spring and a pair of relatively movable pivotally mounted armature members controlled by said magnet windings whereby said shunt winding actuates one of said armature members to place said spring under stress and thereby

tend to close said switch and said series winding retains the other armature member 15 in its normal position to prevent the closing of said switch so long as the current traversing said series coil exceeds a predetermined value.

10. In testimony whereof, I have hereunto 20 subscribed my name this 21st day of March, 1911.

RAGNAR WIKANDER.
